UNITED STATES PATENT OFFICE.

ELI B. COUP, OF MCKEESPORT, PENNSYLVANIA.

GOVERNOR FOR AIR-COMPRESSORS.

No. 914,116.

Specification of Letters Patent.

Patented March 2, 1909.

Application filed December 26, 1907. Serial No. 408,082.

To all whom it may concern:

Be it known that I, ELI B. COUP, a citizen of the United States of America, residing at McKeesport, in the county of Allegheny and State of Pennsylvania, have invented certain new and useful Improvements in Governors for Air-Compressors, of which the following is a specification, reference being had therein to the accompanying drawing.

10 This invention relates to governors and the object thereof is to provide a governor in a manner as hereinafter set forth for automatically controlling the operation of an air compressor and the engine operating the compressor when a predetermined pressure stage has been reached to overcome any liability of injury to the compressor or to the engine.

Although the governor is designed primarily for the purpose set forth, yet it is also adapted for any purposes for which it is found applicable for example, in connection with a compound locomotive for controlling the admission of steam to the locomotive cylinder.

With the foregoing and other objects in view, the invention consists of the novel construction, combination and arrangement of parts, hereinafter more specifically described and illustrated in the accompanying drawings, wherein is shown the preferred embodiment of the invention, but it is to be understood that changes, variations and modifications can be resorted to which come within the scope of the claims hereunto appended.

In the drawings, Figure 1 is a vertical sectional view of a governor constructed in accordance with this invention. Fig. 2 is a front elevation thereof partly in section. Fig. 3 is a vertical sectional view of the governor valve. Fig. 4 is a top plan showing the adaptation of the governor in connection with an engine, an air compressor and a receiver. Fig. 5 is a sectional detail of one end of the cylinder of the compressor showing an unloading valve. Fig. 6 is an enlarged view of the unloading valve, and, Fig. 7 is a sectional view illustrating a steam controlling device for the engine.

50 The air receiver A, the air compressor B, the engine C and steam controlling device D shown in Fig. 3 are illustrated by way of example so that the adaptation of the governor in accordance with this invention with the said elements referred to can be thoroughly understood. The air compressor B

is provided with the unloading valves E which are illustrated by way of example and in connection therewith it will be said that the head F of the compressor is recessed as at 60 H and in which is arranged a valve seat I for the valve E. The stem of the valve E is indicated by the reference character J and carries a collar K constituting an abutment for one end of the coil spring M which surrounds the stem J and abuts against the seat I. The head F is furthermore provided with a screw-threaded plug N through which extends a plunger O. To the head F is secured a cap P in which extends the plug N 70 and which forms a pressure chamber R adapted to communicate with the governor in a manner hereinafter explained. In Fig. 7 is shown the steam controlling device which has a pipe connection S with a steam supply. The pipe connection S opens into a valve body S¹ provided with a seat S² for valve S³. Projecting from the valve body S¹ is a steam supply pipe S⁴ which communicates with the engine cylinder. The stem of 80 the valve S³ is indicated by the reference character S⁵ and has its outer end pivoted at S⁶ to a lever S⁷ mounted upon a support S⁸ formed integral with the bracket S⁹ which projects from the valve body S¹. Formed integral with the bracket S⁹ is a cylinder S¹⁰ in which is located a piston S¹¹ having a piston rod S¹² which is pivotally connected at its outer end at S¹³ to the lever S⁷. The cylinder S¹⁰ communicates with the governor in a 90 manner hereinafter set forth. The elements referred to in this paragraph are of known construction and no claim is made for the same and they are merely shown so that the function of a governor in accordance with 95 this invention can be thoroughly understood.

Referring to Figs. 1, 2 and 3 of the drawings, in which is illustrated a governor in accordance with this invention, 1 denotes a bracket which is secured upon the base of 100 the compressor B and the said bracket 1 has formed integral therewith or connected thereto a casing 2 having its lower end enlarged at 3 and internally threaded at 4. To the enlarged lower end 3 of the casing 2 is 105 secured the upper end of a valve casing 5, the latter being peripherally threaded at 6 for engagement with the threads 4 of the end 3 of the casing 2. The valve casing 5 at its lower end is formed with a pair of lateral 110 nipples 7, 8 which extend in opposite directions with respect to each other. The

valve casing 5 is furthermore provided with a depending nipple 9; each of the nipples 7, 8 and 9 is interiorly screw-threaded. A pipe 10 is connected to the nipple 7, a pipe 11 connected to the nipple 8 and a pipe 12 attached to the nipple 9. The pipe 10 leads to the cylinder S^{10} of the steam controlling device. The pipe 11 communicates with the chamber R and the pipe 12 communicates with the receiver A. The pipe 10 communicates with the interior of the valve casing 5 through the medium of the ports 13; the pipe 11 communicates with the interior of the valve casing 5 by the port 14; the pipe 12 opens directly into the lower end of the valve casing 5. The lower end of the valve casing 5 is formed with a valve chamber 15 and a valve seat 16. The function of the valve 16 is to close communication between the pipe 12 and the pipes 10, 11, such function is had when the valve 16 engages the seat 14. The valve 16 is provided with a stem 17 which not only extends through the valve casing 5 but also up and through the casing 2, the latter constituting a guide for the upper portion of the stem 17. The stem 17 is formed with an axial bore 18 which opens at its lower end into a pair of laterally extending ports 19 and at its upper end into a pair of laterally extending ports 20, these latter being termed exhaust ports. The stem 17 is furthermore provided with a plurality of collars 21 for the purpose of guiding the stem within the valve casing 5. The collars 21 are arranged on the lower portion of the valve stem 17. The outer end of the stem 17 is provided with a notch or concavity 22 in which engages a depending lug 23 projecting from the lower face of the upper arm of a stirrup 24, the latter being rectangular in contour and surrounding the casing 2 and valve casing 5. The lower arm of the stirrup 24 has depending therefrom a hanger 25 upon which are mounted a plurality of weights 26, the function of which will be hereinafter explained. Intermediate the ends of the valve stem 17 a pair of circumferentially extending grooves 27 is provided and adapted to engage in the said grooves is a pin 28 which extends through an opening provided therefor in the casing 2. The pin 28 is carried by a resilient arm 29 fixed to the stud 30 projecting laterally from the valve casing 2. The function of the pin 28 will be hereinafter explained.

It will be assumed that the air in the receiver A has reached a stage above a predetermined point. It will be evident that the increased pressure in the receiver will cause the shifting of the valve 16 off its seat 14. Such action will establish communication between the pipes 10, 11 and 12, the pressure upon the valve 16 overcoming the pressure exerted against the stem 17 and the valve 16 by the weighted stirrup 24. As

communication has now been established between the receiver and the pipes 10, 11, the pressure of air entering the pipe 10 through the ports 13 will pass to the cylinder S^{10} elevating the piston S^{11} , rocking the lever S^7 , lowering the stem S^5 and seating the valve S^3 against the seat S^2 , thereby shutting off the steam supply to the engine cylinder and discontinuing the operation of the engine. The air pressure entering the pipe 11 through the ports 14 will pass to the chamber R, shift the plunger N causing said plunger to open the valve E thereby discontinuing the operation of the air compressor until the pressure of air in the receiver A becomes normal. When the pressure in the receiver A has been reduced, the valve 16 will be caused to assume its seat through the medium of the weighted stirrup 24. This will allow the exhaust of air from the cylinder S^{10} and chamber R through the pipes 10, 11, ports 19, axial bore 18 and exhaust ports 20 and allow the engine to again take steam to further operate the compressor. In order that the engine may start slightly in advance of the compressor the two ports 13 are provided, to rapidly exhaust the air, whereas but a single port 14 is employed for exhausting the air from the pipe 11.

To insure a positive movement of the stem 17 the pin 19 and the resilient arm are provided, these two elements holding the stem until a sufficient high or low pressure of air has been obtained to raise or release the stem.

What I claim is:

1. A governor for the purpose set forth comprising a valve casing having a plurality of nipples at one end, one of said nipples opening directly into the interior of the casing, said casing furthermore provided with a laterally extending port and a pair of laterally extending ports, another of said nipples communicating with the interior of said valve casing through said single port and the other of said nipples communicating with the interior of said valve casing through said pair of laterally extending ports, said casing furthermore provided with a valve seat below said ports, a valve normally engaging said seat, a valve stem projecting from the valve and provided with an axial bore and further provided with upper and lower ports, and a weighted stirrup engaging with the valve stem for normally maintaining the valve in engagement with its seat.

2. A governor for the purpose set forth comprising a valve casing having a plurality of nipples at one end, one of said nipples opening directly into the interior of the casing, said casing furthermore provided with a laterally extending port and a pair of laterally extending ports, another of said nipples communicating with the interior of said valve casing through said single port and the

other of said nipples communicating with the interior of said valve casing through said pair of laterally extending ports, said casing furthermore provided with a valve seat below 5 said ports, a valve normally engaging said seat, a valve stem projecting from the valve and provided with an axial bore and further provided with upper and lower ports, a weighted stirrup engaging with the valve 10 stem for normally maintaining the valve in engagement with its seat, said valve adapted to be shifted from its seat by fluid pressure, said stirrup adapted to shift the valve to its seat when the pressure is reduced upon the 15 valve, and spring-pressed means extending in said casing for temporarily holding the stem in its shifted position.

3. A governor for the purpose set forth comprising a valve casing formed at one end 20 with a depending nipple and with a pair of laterally extending nipples, said depending nipple adapted to communicate with the fluid pressure supply, one of said laterally extending nipples adapted to communicate with 25 the steam controlling device of an engine, and the other of said laterally extending nipples adapted to communicate with the unloading valve mechanism of an air compressor, said casing furthermore provided 30 with a pair of ports for establishing communication between one of said laterally extending nipples and the interior of the casing and said casing furthermore provided with a port for establishing communication between 35 the other laterally extending nipple and the interior of the casing, said casing further having a valve seat, a valve arranged within said casing and adapted to engage said seat below said ports and when in engagement with 40 said seat shutting off communication between the laterally extending nipples and the other of said nipples, said valve shifting from its seat by fluid pressure whereby communication is established between said laterally extending nipples and the fluid pressure supply, and spring-pressed means extending in said casing for normally maintaining said valve in engagement with its seat.

4. A governor for the purpose set forth 50 comprising a valve casing formed at one end with a depending nipple and with a pair of laterally extending nipples, said depending nipple adapted to communicate with the fluid pressure supply, one of said laterally extending nipples adapted to communicate with the steam controlling device of an engine, and the other of said laterally extending nipples adapted to communicate with the unloading valve mechanism of an air compressor, said 55 casing furthermore provided with a pair of ports for establishing communication between one of said laterally extending nipples and the interior of the casing and said casing furthermore provided with a port for establishing 60 communication between the other laterally

extending nipple and the interior of the casing, said casing further having a valve seat below said ports, a valve arranged within said casing and adapted to engage said seat and when in engagement with said seat shutting off communication between the laterally extending nipples and the other of said nipples, said valve shifted from its seat by fluid pressure whereby communication is established between said laterally extending nipples and the fluid pressure supply, a valve stem projecting from said valve and provided with means for exhausting pressure from said valve casing when the valve is seated, and means for normally maintaining said valve against its 80 seat.

5. A governor for the purpose set forth comprising a valve casing formed at one end with a depending nipple and with a pair of laterally extending nipples, said depending 85 nipple adapted to communicate with the fluid pressure supply, one of said laterally extending nipples adapted to communicate with the steam controlling device of an engine, and the other of said laterally extending 90 nipples adapted to communicate with the unloading valve mechanism of an air compressor, said casing furthermore provided with a pair of ports for establishing communication between one of said laterally extending 95 nipples and the interior of the casing and said casing furthermore provided with a port for establishing communication between the other laterally extending nipple and the interior of the casing, said casing further having a valve seat below said ports, a valve arranged within said casing and adapted to engage said seat and when in engagement with said seat shutting off communication between the laterally extending nipples and the other of said nipples, said valve shifted from its seat by fluid pressure whereby communication is established between said laterally extending nipples and the fluid pressure supply, a valve stem projecting from said 100 valve and provided with means for exhausting pressure from said valve casing when the valve is seated, and a weighted stirrup engaging with said valve stem for normally maintaining the valve against its seat.

6. A governor for the purpose set forth comprising a valve casing formed at one end with a depending nipple and with a pair of laterally extending nipples, said depending 115 nipple adapted to communicate with the fluid pressure supply, one of said laterally extending nipples adapted to communicate with the steam controlling device of an engine, and the other of said laterally extending nipples adapted to communicate with the unloading valve mechanism of an air compressor, said casing furthermore provided with a pair of ports for establishing communication between one of said laterally extending 120 nipples and the interior of the casing and said casing furthermore provided with a port for establishing communication between the other laterally extending nipples and the interior of the casing 125

and said casing furthermore provided with a port for establishing communication between the other laterally extending nipple and the interior of the casing, said casing further having a valve seat below said ports, a valve arranged within said casing and adapted to engage said seat and when in engagement with said seat shutting off communication between the laterally extending nipples and 10 the other of said nipples, said valve shifted from its seat by fluid pressure whereby communication is established between said laterally extending nipples and the fluid pressure supply, a valve stem projecting from said

valve and provided with means for exhausting pressure from said valve casing when the valve is seated, a weighted stirrup engaging with said valve stem for normally maintaining the valve against its seat, and spring-pressed means extending in said casing for 20 temporarily holding the valve stem in its adjusted position.

In testimony whereof I affix my signature in the presence of two witnesses.

ELI B. COUP.
